PANEL BOX FOR REFRIGERATOR CONTROL

Gus Romanias, 2611 S. Grant St., Arlington, Va. 22202,
and Herman H. Gorham, 5616 Bouffant Blvd., Alexandria, Va. 22311

Filed Nov. 28, 1969, Ser. No. 20,302

Term of patent 14 years

Int. Cl. D13—03

U.S. Cl. D26—13

Fig. 1

Fig. 2

Fig. 3

4
FIG.

FIG. 1 is a front elevational view of the panel box for refrigerator control in a closed position showing my new design;

FIG. 2 is a right side elevational view thereof;

FIG. 3 is a top plan view thereof;

FIG. 4 is a rear elevational view of the panel box for refrigerator control as described in FIG. 1.

The sides opposite to the sides shown in FIGS. 2 and 3 are identical to these respective figures.

I claim:

The ornamental design for a panel box for refrigerator control, as shown and described.
